UNITED STATES PATENT OFFICE.

WILLIAM KELLY, OF SARANAC, MICHIGAN.

HARROW-TOOTH.

SPECIFICATION forming part of Letters Patent No. 231,816, dated August 31, 1880.

Application filed July 22, 1880. (No model.)

To all whom it may concern:

Be it known that I, WILLIAM KELLY, of Saranac, in the county of Ionia and State of Michigan, have invented certain new and useful Improvements in Harrow-Teeth; and I do hereby declare that the following is a full, clear, and exact description thereof, reference being had to the accompanying drawings, and to the letters of reference marked thereon, which form part of this specification, in which—

Figure 1 is a perspective, and Fig. 2 a cross-section, showing the method of attaching the teeth to the wood-work of the cultivator.

The nature of my invention consists in the peculiar construction of cultivator-teeth—that is to say, in making twin or double teeth from one and the same piece of spring metal, which admits of their being secured by one fastening device, all substantially as hereinafter to be fully set forth.

To enable others skilled in the art to which my invention relates to make and use it, I will now proceed to describe its construction and operation.

25 A represents a piece or strip of spring metal, each end thereof being formed or fashioned into a spear-like tooth, b. The shape of these teeth may, however, be varied without in the least departing from the essence of my invention.

30 The strip or tooth A should be of sufficient length to admit of its having one or more spiral coils, in such a manner that the teeth b b will straddle or project downward upon opposite sides of the cross bar or beam C, while the coil may extend some little distance above it,

as fully shown in the drawings. The two ends of strip A may reach to the same or different planes, as shall be preferred. On the under side of bar C is formed a notch or groove, in which the strip A is placed and over which 40 the plate d is screwed.

It will thus be seen that this method of constructing cultivator-teeth enables me to secure the pair with one fastening, which effects saving in both wood and metal, while the simplicity of the fastening itself renders it very easy to remove or adjust the teeth when necessary to do so.

I am aware that it is not new, broadly, to construct a harrow-tooth from one piece of 50 spring metal, and therefore do not claim such as my invention; but

What I do claim as new, and desire to secure by Letters Patent, is—

1. A double harrow-tooth formed from one 55 piece of coiled spring metal, the points thereof being upon the same horizontal plane, but not upon the same vertical line, substantially as herein set forth.

2. The combination, with the beam C of a 60 harrow, of the double tooth A, formed, as described, from one piece of spring metal, and secured to the beam, substantially in the manner and for the purpose set forth.

In testimony that I claim the foregoing as 65 my own I affix my signature in presence of two witnesses.

Witnesses: WILLIAM KELLY.
